GARMENT

Murray Bloom, New York, N. Y.

Application August 1, 1944, Serial No. 547,588

3 Claims. (Cl. 2—73)

This invention relates to garments, and has for its principal object the provision of a novel body garment for ladies having attached skirt and waist portions which are so formed as to drape the body in a superior fashion and bring out the best lines of the wearer. The garment is intended primarily as a slip, although garments embodying the present invention may be formed as night-gowns, or dresses as well.

A garment embodying the features of the present invention has a bias effect in certain portions thereof such as to prevent the garment from riding up when the wearer sits down. It is also formed in such a manner as to take care of the increased girth of the wearer when she sits down, thus avoiding any binding or pinching action, without, however, reducing the effective length of the garment. Another object of the present invention is to provide a garment having a minimum number of seams, thus reducing the overall cost of the garment, while, at the same time, preserving all of the effective lines of the body.

Specifically, the garment of the present invention is what may be termed a "two-gore slip" as distinguished from the four-gore type of slip which hitherto has given fairly satisfactory results. The front skirt portion is formed in a single piece, and is provided with laterally-extending portions at its upper end which extend into the waist-encircling section of the garment. This front skirt portion is preferably, though not necessarily, formed on the bias of the material relative to the front median line of the garment. The balance of the garment, except for the brassière section, is preferably formed in a single piece, and is joined along its two opposed, substantially-vertical edges to the opposed, vertical edges of the front skirt section. By thus forming the major portion of the garment from two blanks only, the number of seams required is greatly reduced, and the garment has a circular sweep which is highly flattering to the human figure, as well as being remarkably comfortable to the wearer.

Another object of the present invention is the provision of an improved body garment, the several blanks of which are so formed as to effect a distinct saving in material, while, at the same time, providing a full body garment so formed as to relatively snugly hug the figure, particularly over the abdomen, and to preserve this fine-fitting quality regardless of whether the wearer is sitting, standing, or is engaged in some active maneuvers, such as dancing, walking or bending.

Other objects and advantages of the invention

will be pointed out hereinafter, or will become apparent as the specification proceeds.

In the drawing:

Fig. 1 is a front elevation of the improved garment of the present invention.

Fig. 2 is a rear elevation thereof.

Fig. 3 is a plan view of a blank forming the rear and side skirt sections of the garment.

Fig. 4 is a plan view of a blank forming the front skirt section.

Fig. 5 is a plan view of a blank forming the brassière section.

Fig. 6 is a plan view of a blank forming the rear waist section.

The blank forming the front skirt section is illustrated at 10 in Fig. 4, and includes a curved lower edge 11 and opposed, substantially-straight side edges 12 which are somewhat inwardly inclined as they proceed upwardly. The blank further includes lateral extensions 13 at the upper end thereof defined by upwardly and outwardly-extending edges 14, substantially-vertical edges 15, and upper curved edges 16 which meet at the upper center of the blank defined by point 17. The central longitudinal line A—A of the blank forms the front median line of the garment. This blank, as was earlier pointed out, is desirably, though not necessarily, formed on a bias relative to such front median line A—A.

30 The blank forming the side and rear skirt sections is designated as 21 in Fig. 3, and includes a lower vertical edge 22, upwardly and inwardly-inclined, substantially-straight side edges 23, and upper edges 24 meeting at central point 25. 35 Edges 24 are desirably, though not necessarily, concavely curved. This blank is desirably formed so that the grain line of the material is substantially parallel with the line B—B which forms the back median line of the garment. In the 40 preferred construction, this blank is formed in one piece, although if this is inconvenient due to considerations of material width, or otherwise, it could be formed in two pieces which might, for example, be joined together along line B—B 45 to form a central, rear, vertical seam. The fitting qualities of the garment, however, are considerably enhanced by forming this blank in one piece.

The brassière section may be formed from 50 either two or four of the blanks 28 shown in Fig. 5, depending upon whether a single or double yoke effect is desired. The blank shown in Fig. 5 is formed for the right-hand side of the garment when viewed from the front, and a similar blank, 55 reversed as to position, is employed for the op-

posite side of the brassière section. The blank includes side edge 29 which coincides with the front median line of the garment, and upper edges 30 and 31 which intersect at point 32, to which point the shoulder strap may be secured. The blank further includes side edge 33 which, in the assembled garment, defines the only side seam of the garment, and an irregularly-shaped lower edge 34. Blank 36, of which two or four are employed for the garment, forms the rear waist section and is of somewhat irregular rectangular shape, and formed with edges 37, 38, 39 and 40.

Edges 12 of blank 10, and edges 23 of blank 21, are of substantially the same length, and are joined together to form seams 42 which are disposed on opposite sides of the front median line of the garment. Each of upper edges 24 of blank 21 is of a length substantially equal to the combined lengths of each of edges 14 in blank 10, and lower edge 40 of blank 36. Such edge 24 and edges 14 and 40 are joined together to form stitch lines 43 at the front of the garment, and 44 at the rear of the garment. Next, edge 15 of lateral extension 13, and edge 33 of blank 28, are joined to edge 37 of blank 36 to form a short side seam 45. Superior fitting qualities are provided if the blanks are so formed as to cause this seam to be located in the rear section of the garment, rather than have it coincide with the true side median line. The remaining edges 38 and 39 of blanks 36 form half of the upper edge of the rear waist section of the garment. Next, edges 29 of each of blanks 28 are joined together to form stitch line 46, and finally, lower edge 34 of blank 28, and upper edge 16 of lateral extension 13, are joined together to form stitch line 47. Blank 28 may be provided with a plurality of notches or other indicating marks 50 to designate the locations of horizontal darts 51 which aid in shaping the brassière section. Likewise, lower edge 34 of blank 28 may have a plurality of markings 54 which indicate the locations of the vertical darts 55. The garment is completed by providing shoulder straps 56.

From the foregoing, it will be clear that the entire upper portion of blank 10 forms a true midriff section which is on the bias, and which snugly fits the abdomen of the wearer. The seams are so arranged as to cooperate with each other to yield to stresses in the garment, regardless of the position or condition of activity or inactivity of the wearer.

While one form or embodiment of the invention has been shown and described herein for illustrative purposes, and the construction and arrangement incidental to a specific application thereof have been disclosed and discussed in detail, it is to be understood that the invention is limited neither to the mere details or relative arrangement of parts, nor to its specific embodiment shown herein, but that extensive deviations from the illustrated form or embodiment of the invention may be made, without departing from the principles thereof.

What I claim is:

1. A body garment formed from a plurality of blanks of material, including an elongated blank forming the front skirt portion and provided at its upper end with outwardly-disposed lateral extensions which extend into the waist section and terminate substantially at the side of the

garment, a blank forming the side and rear skirt section, the opposed vertical edges of each of such blanks being upwardly and inwardly inclined, the adjacent edges of such blanks being substantially

5 straight and being joined together to form substantially vertical seams disposed on opposite sides of the front median line of the garment, said latter blank being formed with two upwardly and inwardly-inclined upper edges which are concavely curved and which intersect at the upper, rear, central point of the garment, and blanks forming the brassière and rear waist sections of the garment, the lower edges of the latter blanks and the lower edges of the lateral extensions being substantially straight and being secured to the concavely-curved upper edges of the blank forming the rear skirt section, the lower edges of the brassière section being secured to the upper edge of the front skirt blank.

20 2. A body garment formed from a plurality of blanks of material, including an elongated blank forming the front skirt portion and provided at its upper end with lateral extensions which extend into the waist section and terminate substantially at the side of the garment, a blank forming the side and rear skirt section, the opposed vertical edges of each of such blanks being upwardly and inwardly inclined, the adjacent edges of such blanks being of substantially the same length and being joined together to form substantially vertical seams disposed on opposite sides of the front median line of the garment, said latter blank being formed with two upwardly and inwardly-inclined upper edges which intersect at the upper, rear, central point of the garment, and blanks forming the brassière and rear waist sections of the garment, the lower edges of the latter blanks and the lower edges of the lateral extensions being secured to the upper edges of the blank forming the rear skirt section, the lower edges of the brassière section being secured to the upper edge of the front skirt blank.

30 3. A body garment formed from a plurality of blanks of material, including an elongated blank forming the front skirt portion and provided at its upper end with lateral extensions which extend into the waist section and terminate substantially at the side of the garment, the upper portion of such blank including the lateral extensions forming a midriff section, the grain line of which is at an angle to the front median line of the garment, the opposed vertical edges of the blank being upwardly and inwardly inclined, a blank forming the side and rear skirt section, the adjacent edges 35 of such blanks being joined together to form substantially vertical seams disposed on opposite sides of the front median line of the garment, the grain line of the material in the rear skirt blank adjacent such edges lying generally parallel with such edges, said latter blank being formed with two upwardly and inwardly-inclined upper edges which intersect at the upper, rear, central point of the garment, and blanks forming the brassière and rear waist sections of the garment, the lower edges of the latter blanks and the lower edges of the lateral extensions being secured to the upper edges of the blank forming the rear skirt section, the lower edges of the brassière section being secured to the upper edge of the front skirt blank, and darts formed in the lower edges of the brassière section.

MURRAY BLOOM.
